UNITED STATES PATENT OFFICE

136,006

DESIGN FOR A GREETING CARD OR SIMILAR ARTICLE

Alvin Barker, Cincinnati, Ohio

Application March 5, 1943, Serial No. 109,676

Term of patent 3½ years

To all whom it may concern:

Be it known that I, Alvin Barker, a citizen of the United States of America and a resident of Cincinnati, in the county of Hamilton and State of Ohio, have invented a new, original, and ornamental Design for a Greeting Card or Similar Article, of which the following is a specification, reference being made to the accompanying drawing, forming a part thereof.

The figure is a perspective view of a greeting card showing my new design.

I claim:

The ornamental design for a greeting card or similar article, as shown.

ALVIN BARKER.
